(No Model.)

W. B. BRAGDON,
ELECTRIC WIRE SUPPORT.

No. 479,052.

Patented July 19, 1892.

THE NORRIS PETERS CO., PHOTO-LITHO., WASHINGTON, D. C.

UNITED STATES PATENT OFFICE.

WILLIAM B. BRAGDON, OF CUMBERLAND MILLS, MAINE.

ELECTRIC-WIRE SUPPORT.

SPECIFICATION forming part of Letters Patent No. 479,052, dated July 19, 1892.

Application filed March 4, 1892. Serial No. 423,760. (No model.)

To all whom it may concern:

Be it known that I, WILLIAM B. BRAGDON, a citizen of the United States, residing at Cumberland Mills, in the county of Cumberland 5 and State of Maine, have invented certain new and useful Improvements in Tripods for Supporting Electric-Wire Insulators; and I do declare the following to be a full, clear, and exact description of the invention, such as will 10 enable others skilled in the art to which it appertains to make and use the same, reference being had to the accompanying drawings, and to the letters of reference marked thereon, which form a part of this specification.

15 This invention relates to certain new and useful improvements in devices for supporting electric wires; and it has for its object to provide a simple form of tripod, which is designed especially for use in conducting wires 20 over the roofs of buildings.

The device is simple and cheap of construction, of few parts, and adapted to be readily put up, and when not required for use the several parts may be separated and packed 25 within small space, thus rendering it convenient for storage or transportation.

To these ends and to such others as the invention may pertain the same consists in the peculiar construction and in the novel combination, arrangement, and adaptation of parts, 30 all as more fully hereinafter described, shown in the accompanying drawings, and then specifically defined in the appended claims.

The invention is fully illustrated in the accompanying drawings, which, with the letters 35 of reference marked thereon, form a part of this specification, like letters of reference indicating the same parts throughout the several views, and in which drawings—

40 Figure 1 is a side view of a wire-supporting tripod embodying my improvements. Figs. 2, 3, 4, and 5 are enlarged detail views of the several castings, which will be more particularly hereinafter referred to.

45 Reference now being had to the details of the drawings by letter, A represents an ordinary cross-bar, such as is commonly employed for supporting electric-wire insulators, as shown at A'. This cross-bar is supported 50 upon the tripod consisting of the castings B C, the rods or legs E, and the castings D,

which form the feet or supports for the legs or rods E.

Each of the castings D consists of a base portion d, which may be either of the circular 55 form shown, or, if preferred, may be rectangular and provided at intervals around its outer edge with recesses d', within which are placed the nails, bolts, or screws which are employed in securing the casting to the roof of the building. The body portion e of the casting is inclined at an angle from the base portion, is hollow to permit of the passage of the rod E, and is provided with an enlarged chamber e² for the reception of the nut e' upon the lower end of 60 the rod.

The casting C consists of a body portion C', having at its center an opening C² for the passage of the bolt which is used in securing together the parts of the tripod, as will be presently explained, and at its outer edge the bifurcated and slightly-upwardly-inclined arms or projections C³. The upper ends of the legs or rods E are received within the bifurcations of the said arms C³ and are retained 75 therein by means of the nuts C⁴, which are placed upon the said rods both above and below the arms.

The casting B, which forms a support for the cross-bar A, consists of the body portion 80 B', having at its ends upwardly-extended arms or projections B², which engage openings provided for their reception in the lower face of the cross-bar, and upon the lower face of the said casting B are provided a series of 85 bosses or projections B³, which engage corresponding apertures in the casting C.

In assembling the parts the castings D are first secured to the lower ends of the rods E. The casting C is next attached to the upper 90 ends of the rods. The part B is then placed upon the upper face of the casting C, and upon said casting B is placed the cross-bar A. A bolt G is then passed through the cross-bar A and extended downward through openings 95 in the castings B and C, and the parts thus united are drawn securely together by means of a nut upon the upper end of the rod G, as shown.

Having thus described my invention, what 100 I claim to be new, and desire to secure by Letters Patent, is—

1. In a device of the character described, in combination, the rods E, the castings D, forming the feet of the tripod and adapted to be bolted to the lower ends of the rods E, and 5 the casting C, having body portion C' and inclined bifurcated arms, the upper ends of the rods being secured within the bifurcations of said arms by nuts upon the rods, substantially as described, and for the purpose specified.
- 10 2. The herein-described tripod for supporting electric-wire insulators, the same comprising, in combination, the rods E, forming the legs of the tripod, the castings D, detachably secured to the lower ends of the rods E and 15 adapted to be secured to the roof of a building, the casting C, having inclined bifurcated

arms to receive the upper ends of the rods E, the nuts C' upon said rods, the casting B, having upwardly-extended arms or projections B² and bosses B³ upon its lower face, said bosses being adapted to engage recesses in the casting C, the cross-bar A, seated upon the casting B, and the bolt G, passed through said cross-bar and castings and serving to hold the same together, substantially as described. 20 25

In testimony whereof I affix my signature in presence of two witnesses.

WILLIAM B. BRAGDON.

Witnesses:

S. F. HOPKINSON,
WILLIAM LYONS.
